UNITED STATES PATENT OFFICE.

MICHAEL PROVICH, OF CHICAGO, ILLINOIS.

STOPPER.

1,388,890.

Specification of Letters Patent. Patented Aug. 30, 1921.

Application filed December 20, 1919. Serial No. 346,260.

To all whom it may concern:

Be it known that I, MICHAEL PROVICH, a citizen of Jugoslavia, residing at Chicago, in the county of Cook and State of Illinois, 5 have invented a new and useful Improvement in Stoppers, of which the following is a specification.

My invention relates, more particularly, to devices for temporarily stopping the 10 flow of gaseous fluid through a pipe, as for example the flow of gas through a gas main, as in the case of repairs or extensions to the pipe lines; and my primary object is to provide a novel, simple 15 and economical construction of device for this purpose which may be quickly and effectively applied to use, and by the use of which inconvenience and danger to the workman from escaping gas may be greatly 20 reduced.

Referring to the accompanying drawings:—Figure 1 is a face view in elevation of a device embodying my invention, the device being shown in a gas main in the position 25 it occupies when performing its function as a stopper, the section being taken at the line 1 on Fig. 2 and viewed in the direction of the arrow. Fig. 2 is an edge view of the device showing the pipe to which it is 30 applied in longitudinal section. Fig. 3 is a view like Fig. 1 of the device, showing it by full lines in the position its parts assume prior to its application to stopper-forming position, and by dotted lines the positions of 35 its parts when positioned in a pipe as shown in Fig. 1. Fig. 4 is a section taken at the line 4—4 on Fig. 1 and viewed in the direction of the arrow. Fig. 5 is a section taken at the line 5—5 on Fig. 1 and viewed in the 40 direction of the arrow; and Fig. 6, a section taken at the line 6—6 on Fig. 1 and viewed in the direction of the arrow.

In accordance with the preferred, illustrated, embodiment of my invention the device is formed of a frame 7 comprising the generally parallel side members 8—8 united at their upper ends by the cross-piece 9 containing a centrally-disposed, screw-threaded opening 9^a, and the laterally opening slots 10 and 11 at opposite sides of the opening referred to, and a ring 12 externally screw-threaded as represented and having upwardly-extending, diametrically-opposed lugs 13 connected with the lower 50 ends of the frame sides 8 in overlapped relation, as by the screws 14, one of the frame

sides 8 being provided with a screw 15 screwing therein for a purpose hereinafter explained. The frame thus provided is equipped at its lower end with a diaphragm 60 16 shown as, and by preference, in the form of a bag formed of opposed sections 17 of flexible material, as for example fabric such as close-grained duck, having their edges connected, and bound by, a rubber strip 18, 65 the fabric and rubber strip being secured together in any suitable way, as for example by sewing them together or vulcanizing them into an integral structure. The upper, open, end of the bag, this end being restricted as 70 shown, is held by a tight joint to the threaded ring 12, as by clamping it thereto by means of an expansible, segmental, ring 19, as of wire, between which and the inner surface of the ring 12, the wall of the open 75 mouth of the bag extends, the ring 19 opposing annular grooves 20 in the outer surfaces of arc-shaped members 21 located in the frame 7 and pressed against the bag, and held in place, by the screws 14, thereby providing means whereby the bag 16 is removable yet firmly held in place on the frame 7. One of the members 21 is secured to the ring 19 midway between the ends of the latter, and the other engages the ends of the wire 80 85 forming this ring.

The device further comprises a member adapted to be operated to force the bag 16 into tight-joint-forming position in the pipe to be closed, this member being preferably 90 formed of a frame 22 comprising the generally parallel, longitudinally extending, bars 23 connected at their lower ends by a cross pin 24 and at their upper ends by a cross-piece 25 formed integrally therewith, the 95 bars 23 at the upper end of the frame 22 being spaced apart a distance substantially equal to the distance between the two slots 10 and 11, adapting the frame 22 to be assembled with the frame 7, as hereinafter described. The bars 23 carry a cross-pin 26, shown in the form of a bolt, located intermediate the upper and lower ends of the frame 22 and extending at its ends into slots 27 in the frame bars 23, this cross-pin 100 being slidable in these slots in a direction lengthwise of the frame 22. Pivotally connected with the pin 26 are links 28 which extend therefrom in opposite directions, these links, which are preferably 110 of general arc-shape, preferably having sleeve sections 29 which surround the pin 26

and by which the pivotal connection therewith is afforded. The links 28 coöperate with members 30 for coöperation with the diaphragm 16 for forcing the latter into a tight-joint-forming condition relative to the inner surface of the pipe with which the device is to be used. The members 30 which, in the particular construction illustrated, operate to cause the diaphragm to assume the position stated, upon operating them to spread condition within the bag 16, are preferably formed of comparatively springy wire, each being at one end of general semi-circular shape as shown at 31, and at its opposite end of reversely curved form as shown at 32. The members 30 are pivoted at eyes 33 to the cross-pin 24 at the lower ends of their portions 31, and at eyes 34 at their opposite ends to the pins 35 carried at the outer ends of the links 28, the members 30 being reversely positioned as shown whereby when the links 28 are in the position shown by full lines in Fig. 3, the frame-like structure formed by the members 30 is in very compact and contracted condition, adapting of the insertion of the structure of which these members are parts, into and through, the ring 12 and into the bag 16 through the mouth portion thereof, and when the links 28 are in the position represented by dotted lines in Fig. 3, the members 30 are in the expanded position shown by dotted lines in Fig. 3 wherein the frame-like structure formed of the members 30 assumes an approximately circular form.

The frame 22 has journaled in its cross-piece 25 a threaded rod 36 extending lengthwise of this frame and provided at its outer, upper, end with a circular hand-wheel 37 by which to rotate the rods 36 and a shoulder portion 38 bearing against the top of the cross-piece 25, the lower end of this rod being adapted to screw into the threaded opening 9^a in the cross-piece 9, the rod 36 which is provided with a nut 39 to prevent it from becoming disconnected from the frame 22, being provided for a purpose hereinafter explained.

One of the links 28 is provided with a screw-threaded rod 40 journaled in a slot 28^a therein to extend crosswise thereof, the threaded rod 40 having collar sections 41 spaced apart and arranged at opposite sides of the link through which this rod extends, to permit the rod 40 to be rotated on this link but prevent it from becoming disconnected therefrom, the outer end of this rod having a hand-wheel 42 by which it may be rotated. The opposite, threaded, end of the rod 40 is adapted to screw into a threaded opening 43 in the other link 28, the device just described operating as a means for forcibly drawing the links 28 together when this device is positioned as shown in Fig. 1.

The operation of the device is as follows: 65 The operator at the place where the stopper is to be applied to the pipe, as for example a gas main represented at 44, taps the pipe as indicated at 45 to provide the screw-threaded opening therein shown. He then 70 introduces the bag-diaphragm 16 in crumpled condition into and through the tap opening 45 and into the interior of the pipe 44, thereupon screwing the ring 12 into this tap-hole to the position shown in the drawings, wherein the bag 16 extends crosswise 75 of the pipe 44. In accordance with the preferred manner of using the device, the operator, assuming the structure formed of the frame 22, links 28 and the expanding 80 members 30, to be disconnected from the frame 7, adjusts the links 28, the rod 40 being disconnected at its threaded extremity from the adjacent link 28, the one at the left-hand side of Fig. 1, to cause these links 85 to assume the outwardly spread position, and the members 30 the contracted position shown by full lines in Fig. 3, the pivot-pin 26 in this operation sliding downwardly in the slots 27. With this part of the structure thus positioned, the operator introduces it at its lower end into and through the ring 12, and thereupon swings the links 28 toward each other with the result of causing these links to rise and the portions 31 of the members 30 to move outwardly. The structure thus introduced into the ring 12 is then bodily swung to a position in which the upper ends of its bars 23 extend into the slots 10 and 11 of the frame 7 as shown, and the operator continues to swing the links 28 toward each other to a position in which the outer threaded end of the rod 40 may be screwed into the opening 43. The threaded rod 36 is then screwed into the threaded opening 9^a and tightened up to cause the frame 22 to be forced at its lower end against the bottom of the diaphragm to insure a tight joint between the latter and the pipe at this point. The operator then tightens the adjusting device formed of the rod 40 to forcibly squeeze the links 28 together with the result of causing the members 30 at their portions 31 to be forced against the inner surface of the bag for effecting a tight joint between the latter and the inner surface of the pipe 44.

In this connection it may be stated that by reason of the fact that the members 30 are constructed and associated with the other 120 operating elements as shown, a tight joint between the diaphragm and the inner surface of the pipe 44 will be produced regardless of slight unevenesses in the pipe, or variations in the internal diameters of the 125 pipes with which the device is to be used within certain limits, it being noted that in the preferred construction illustrated the

- members 30 are disposed at their upper ends in intersecting relation and thus extend at relatively wide angles with relation to the axis of the ring 12, and that the force applied to these members is at the sides of the frame 22 opposite that at which the portions of the members 30 engaging the bag extend.
- After the threaded rod 36 has been screwed down to the position stated, the operator, to insure against the twisting of the frame 22, tightens the screw 15 against the side of this frame. The structure, of which the frame 22 forms a part, may be readily removed from the expanded position described, by unloosening the screws 15, 36 and 40 and swinging the links 28 outwardly in opposite directions to contract the frame-like structure presented by the lower curved portions 31 of the members 30.
- It will be noted that as soon as the plug 12 is screwed into the tap-hole of the pipe, the escape of gas therefrom is prevented, the plugging of this opening against the escape of gas not being dependent upon the operation of the portion of the apparatus which forces the diaphragm 16 into tight engagement with the walls of the pipe, or the employment of any sealing material such as mud or the like which is now commonly used by workmen when a gas main is to be repaired or connections made therewith.
- The work of making repairs on, and connections with, gas mains may be greatly expedited and accomplished with the minimum inconvenience or danger to the workman by employing stopper means according to my invention, and where desired a number of the diaphragm-equipped plugs may be positioned in the pipe, thus closing the tap-holes and the diaphragm-spreading means being applied to position therein as desired, and avoiding danger of the gas escaping after the plugs are in place.
- While I have illustrated and described a particular construction embodying my invention, I do not wish to be understood as intending to limit it thereto as the same may be variously modified and altered without departing from the spirit of my invention, it being my intention to claim my invention as fully and completely as the prior state of the art will permit.
- What I claim as new and desire to secure by Letters Patent is:
1. A device for the purpose set forth, comprising, in combination, a bag-diaphragm containing an opening and equipped at its open end with a hollow member adapted to be secured in the tap-hole of a pipe, and means for causing said bag to be forced into tight-joint-forming condition relative to the inner wall of the pipe.
  2. A device for the purpose set forth, comprising, in combination, a bag-diaphragm containing an opening and equipped at its
  3. A device for the purpose set forth, comprising, in combination, a bag-diaphragm containing an opening and equipped at its open end with a hollow member adapted to be secured in the tap-hole of a pipe, and means extending into said bag for causing the latter to be forced into tight-joint-forming condition relative to the inner wall of the pipe.
  4. A device for the purpose set forth, comprising, in combination, a bag-diaphragm containing an opening and equipped at its open end with a hollow member adapted to be secured in the tap-hole of a pipe, and means adapted to be introduced into said bag through said hollow member for causing said bag to be forced into tight-joint-forming condition relative to the inner wall of the pipe.
  5. A device for the purpose set forth, comprising, in combination, a bag-diaphragm containing an opening and equipped at its open portion with a hollow member adapted to be secured in the tap-hole of a pipe, and expansible means in said bag for causing the latter to be forced into tight-joint-forming condition relative to the inner wall of the pipe.
  6. A device for the purpose set forth, comprising, in combination, a diaphragm, a member to which said diaphragm is connected and adapted to be secured in the tap-hole of a pipe, a second member adapted to engage the lower portion of said diaphragm and movable relative to said first-named member, means on one of said members and engaging the other thereof for forcing said second member inwardly against the portion of said diaphragm at the side thereof opposite said tap-hole, to make a tight joint, and means on said second member for forcing said diaphragm into tight-joint-forming condition relative to the wall of the pipe.
  7. A device for the purpose set forth, comprising, in combination, a diaphragm, a member to which said diaphragm is connected and adapted to be secured in the tap-hole of a pipe, a second member adapted to engage the lower portion of said diaphragm and movable relative to said first-named member, a screw device on one of said members and engaging the other thereof and operating to force said second member inwardly against the portion of said diaphragm at the side thereof opposite said tap-hole, to make a tight joint, and means on said second member for forcing said diaphragm into tight-joint-forming condition relative to the wall of the pipe.
  8. A device for the purpose set forth, com-

prising, in combination, a bag-diaphragm, a hollow member to which said bag-diaphragm is connected and into which it opens, said hollow member being adapted to be secured 5 in the tap-hole of a pipe, a second member extending through said hollow member and into said bag and adapted to engage the lower portion of said bag and movable relative to said first-named member, means on 10 one of said members and engaging the other thereof for forcing said second member inwardly against the portion of said diaphragm at the side thereof opposite said tap-hole, to make a tight joint, and means 15 on said second member for forcing said diaphragm into tight-joint-forming condition relative to the wall of the pipe.

9. A device for the purpose set forth, comprising, in combination, a structure formed 20 of a flexible diaphragm and a hollow member connected therewith and adapted to be secured in a tap-hole of a pipe, and a second structure disconnected from said first-referred-to structure, adapted to be inserted 25 into said member and operable to force said diaphragm into tight-joint-forming condition relative to the inner surface of the pipe.

10. A device for the purpose set forth, comprising, in combination, a structure 30 formed of a flexible diaphragm and a hollow member connected therewith and adapted to be secured in a tap-hole of a pipe, a second structure disconnected from said first-referred-to structure, adapted to be inserted 35 into said member and operable to force said diaphragm into tight-joint-forming condition relative to the inner surface of the pipe, and means releasably connecting said structures together.

40 11. A device for the purpose set forth, comprising, in combination, a structure formed of a flexible diaphragm and a hollow member connected therewith and adapted to be secured in a tap-hole of a pipe, a second 45 structure separate from said first-referred-to structure, adapted to be inserted into said member and operable to force said diaphragm into tight-joint-forming condition relative to the inner surface of the pipe, and 50 means operating upon assembling said structures together to force said second structure inwardly against the portion of the pipe opposite the tap-hole therein.

55 12. A device for the purpose set forth, comprising, in combination, a structure formed of a flexible bag-diaphragm and a hollow member connected with, and opening into, said bag-diaphragm and adapted to be secured in a tap-hole of a pipe, and a second 60 structure, disconnected from said first-referred-to structure, adapted to be inserted into said member and bag-diaphragm and operable to force said diaphragm into tight-joint-forming condition relative to the inner 65 surface of the pipe.

13. A device for the purpose set forth, comprising, in combination, a structure formed of a flexible bag-diaphragm and a hollow member connected with, and opening into, said bag-diaphragm and adapted to be 70 secured in a tap-hole of a pipe, a second structure, disconnected from said first-referred-to structure, adapted to be inserted into said member and bag-diaphragm and operable to force said diaphragm into tight-joint-forming condition relative to the inner surface of the pipe, and means releasably connecting said structures together. 75

14. A device for the purpose set forth, comprising, in combination, a structure 80 formed of a flexible bag-diaphragm and a hollow member connected with, and opening into, said bag-diaphragm and adapted to be secured in a tap-hole of a pipe, a second structure, separate from said first-referred-to 85 structure, adapted to be inserted into said member and bag-diaphragm and operable to force said diaphragm into tight-joint-forming condition relative to the inner surface of the pipe, and means operating upon assembling said structures together to force said second structure inwardly against the portion of the pipe opposite the tap-hole therein. 90

15. A device for the purpose set forth, comprising, in combination, a structure 95 formed of a diaphragm adapted to be introduced into a pipe through a tap-hole therein and a hollow member with which said diaphragm is connected and adapted to be secured in the tap-hole, said structure being 100 constructed and arranged to prevent escape of gas from the pipe through said tap-hole, and means extending through said member for forcing said diaphragm into tight-joint-forming condition relative to the inner surface of the pipe. 105

16. A device for the purpose set forth, comprising, in combination, a structure formed of a bag-diaphragm adapted to be introduced into a pipe through a tap-hole 110 therein and a hollow member with which said bag-diaphragm is connected and into which it opens, said hollow member being adapted to be secured in the tap-hole and said structure being constructed and arranged to prevent escape of gas from the pipe through said tap-hole, and means extending through said member and into said bag-diaphragm for forcing the latter into tight-joint-forming condition relative to the 115 inner surface of the pipe.

17. In a device for the purpose set forth, the combination of a diaphragm adapted to be introduced into a pipe through a tap-hole therein, and means for forcing the diaphragm into engagement with the inner surface of the pipe formed of a member adapted to enter the pipe through the tap-hole, a plurality of curved members each 120 flexibly connected at one end with the inner 125 130

- end of said member, with their curved portions, for operatively engaging said diaphragm, extending outwardly in opposite directions from said member, and links pivoted to said member and flexibly connected with the other ends of said curved members for the purpose set forth.
18. In a device for the purpose set forth, the combination of a diaphragm adapted to be introduced into a pipe through a tap-hole therein, and means for forcing the diaphragm into engagement with the inner surface of the pipe formed of a member adapted to enter the pipe through the tap-hole, a plurality of curved members each flexibly connected at one end with the inner end of said member, with their curved portions, for operatively engaging said diaphragm, extending outwardly in opposite directions from said member, links pivoted to said member and flexibly connected with the other ends of said curved members for the purpose set forth.
19. In a device for the purpose set forth, the combination of a diaphragm adapted to be introduced into a pipe through a tap-hole therein, and means for forcing the diaphragm into engagement with the inner surface of the pipe formed of a member adapted to enter the pipe through the tap-hole, a plurality of curved members each flexibly connected at one end with the inner end of said member, with their curved portions, for operatively engaging said diaphragm, extending outwardly in opposite directions from said member, and links pivoted to said member by a sliding pivot and flexibly connected with the other ends of said curved members.
20. In a device for the purpose set forth, the combination of a diaphragm adapted to be introduced into a pipe through a tap-hole therein, and means for forcing the diaphragm into engagement with the inner surface of the pipe formed of a member adapted to enter the pipe through the tap-hole, a plurality of curved members each flexibly connected at one end with the inner end of said member, with their curved portions, for operatively engaging said diaphragm, extending outwardly in opposite directions from said member, links pivoted to said member by a sliding pivot and flexibly connected with the other ends of said curved members.
21. In a device for the purpose set forth, the combination of a diaphragm adapted to be introduced into a pipe through a tap-hole therein, and means for forcing the diaphragm into engagement with the inner surface of the pipe formed of a member adapted to enter the pipe through the tap-hole, a plurality of curved spring members each flexibly connected at one end with the inner end of said member, with their curved portions, for operatively engaging said diaphragm, extending outwardly in opposite directions from said member, and links pivoted to said member and flexibly connected with the other ends of said curved members for the purpose set forth.
22. In a device for the purpose set forth, the combination of a diaphragm adapted to be introduced into a pipe through a tap-hole therein, and means for forcing the diaphragm into engagement with the inner surface of the pipe formed of a member adapted to enter the pipe through the tap-hole, a plurality of curved members each pivotally connected at one end with the inner end of said member with their curved portions, for operatively engaging said diaphragm, extending outwardly in opposite directions from said member, and links pivotally connected to said member and pivotally connected with the other ends of said curved members.
23. In a device for the purpose set forth, the combination of a diaphragm adapted to be introduced into a pipe through a tap-hole therein, and means for forcing the diaphragm into engagement with the inner surface of the pipe formed of a longitudinally slotted member adapted to enter the pipe through the tap-hole, a plurality of curved members each flexibly connected at one end with the inner end of said member with their curved portions, for operatively engaging said diaphragm, extending outwardly in opposite directions from said member, links flexibly connected with the other ends of said curved members, and a pivot device connected with the other ends of said links and slidably in the slotted portion of said member.
24. In a device for the purpose set forth, the combination of a bag-diaphragm adapted to be introduced into a pipe through a tap-hole therein, and means extending into said bag-diaphragm for forcing the latter into engagement with the inner surface of the pipe formed of a member adapted to enter said diaphragm through the tap-hole, a plurality of curved members each flexibly connected at one end with the inner end of said member with their curved portions, for operatively engaging said diaphragm, extending outwardly in opposite directions from said member, and links pivoted to said member and flexibly connected with the other ends of said curved members.
25. In a device for the purpose set forth, the combination of a bag-diaphragm adapted to be introduced into a pipe through a tap-hole therein, and means extending into said bag-diaphragm for forcing the latter into engagement with the inner surface of the pipe formed of a member adapted to enter the pipe through the tap-hole, a

- enter said diaphragm through the tap-hole, a plurality of curved members each flexibly connected at one end with the inner end of said member with their curved portions, for operatively engaging said diaphragm, extending outwardly in opposite directions from said member, links pivoted to said member and flexibly connected with the other ends of said curved members, and means engaging said links for moving them relative to each other.
26. In a device for the purpose set forth, the combination of a bag-diaphragm adapted to be introduced into a pipe through a tap-hole therein, and means extending into said bag-diaphragm for forcing the latter into engagement with the inner surface of the pipe formed of a member adapted to enter said diaphragm through the tap-hole, a plurality of curved members each flexibly connected at one end with the inner end of said member with their curved portions, for operatively engaging said diaphragm, extending outwardly in opposite directions from said member, and links pivoted to said member by a sliding pivot and flexibly connected with the other ends of said curved members.
27. In a device for the purpose set forth, the combination of a bag-diaphragm adapted to be introduced into a pipe through a tap-hole therein, a hollow member connected with, an opening into, said bag-diaphragm and adapted to be secured in the tap-hole, and means for forcing said diaphragm into engagement with the inner surface of the pipe formed of a member adapted to enter said bag-diaphragm through said first-referred-to member, a plurality of curved members each flexibly connected at one end with the inner end of said second-referred-to member with their curved portions, for operatively engaging said diaphragm, extending outwardly in opposite directions from the member carrying them, and links pivoted to said last-referred-to member and flexibly connected with the other ends of said curved members.
28. A structure for the purpose set forth, comprising a member, a plurality of curved members each flexibly connected at one end with the inner end of said member, with their curved portions, for operatively engaging a diaphragm, extending outwardly in opposite directions from said member, and links pivoted to said member and flexibly connected with the other ends of said curved members.
29. A structure for the purpose set forth, comprising a member, a plurality of curved members each flexibly connected at one end with the inner end of said member with their curved portions, for operatively engaging a diaphragm, extending outwardly in opposite directions from said member, and links
- having sliding pivoted connection with said member and flexibly connected with the other ends of said curved members.
30. A structure for the purpose set forth, comprising a member, a plurality of curved spring members each flexibly connected at one end with the inner end of said member with their curved portions, for operatively engaging a diaphragm, extending outwardly in opposite directions from said member, and links pivoted to said member and flexibly connected with the other ends of said curved members.
31. A structure for the purpose set forth, comprising a member, a plurality of curved members pivotally connected at one end with the inner end of said member with their curved portions, for operatively engaging a diaphragm, extending outwardly in opposite directions from said member, and links pivoted to said member and pivotally connected with the other ends of the curved members.
32. A structure for the purpose set forth, comprising a longitudinally slotted member, a plurality of curved members flexibly connected at one end with the inner end of said member with their curved portions, for operatively engaging a diaphragm, extending outwardly in opposite directions from said member, links flexibly connected with the other ends of said curved members, and a pivot device connected with the other ends of said links and movable in the slotted portions of said member lengthwise of the latter.
33. A structure for the purpose set forth presenting curved, relatively movable portions for engaging a diaphragm, said portions extending in disconnected intersecting relation, and means for moving said portions outwardly in opposite directions.
34. A structure for the purpose set forth presenting curved, relatively movable portions for engaging a diaphragm, said portions extending in disconnected intersecting relation, and means engaging said portions at the side of said point of intersection opposite that at which they engage the diaphragm.
35. A structure for the purpose set forth presenting curved, relatively movable, portions for engaging a diaphragm, the lower ends of said portions being flexibly connected together and their upper portions extending in disconnected, intersecting, relation, and means for moving said portions outwardly in opposite directions.
36. A structure for the purpose set forth presenting curved, relatively movable, portions for engaging a diaphragm, the lower ends of said portions being flexibly connected together and their upper portions extending in disconnected, intersecting, relation, and means engaging said portions at

the side of said point of intersection opposite that at which they engage the diaphragm.

37. A structure for the purpose set forth, comprising a member, a plurality of curved members each flexibly connected at one end with the inner end of said member, with their curved portions, for operatively engaging a diaphragm, extending outwardly in opposite directions from said member, said curved members extending in intersected relation, and means for shifting said curved members outwardly in opposite directions.

38. A structure for the purpose set forth, comprising, in combination, a bag-diaphragm adapted to be inserted into a pipe through a tap-hole therein, a member adapted to be introduced into said bag-diaphragm, a plurality of curved members flexibly connected at one end with the inner end of said member with their curved portions extending into said diaphragm for forcing the latter into tight-joint-forming condition relative to the inner wall of a pipe, extending outwardly in opposite directions from said member, said curved members extending beyond their pivotal connection with said member, in intersecting relation, and means for shifting said curved members outwardly in opposite directions.

39. A structure for the purpose set forth, comprising, in combination, a bag-diaphragm adapted to be inserted into a pipe through a tap-hole therein, a member adapted to be introduced into said bag-diaphragm, a plurality of curved members flexibly connected at one end with the inner end of said member with their curved portions extending into said diaphragm for forcing the latter into tight-joint-forming condition relative to the inner wall of a pipe, extending outwardly in opposite directions

from said member, said curved members extending beyond their pivotal connection with said member, in intersecting relation, and links pivoted to said member and flexibly connected with the other ends of said curved members.

40. A device for the purpose set forth, comprising, in combination, a bag-diaphragm adapted to be inserted into a pipe through a tap-hole therein and containing an opening, a threaded hollow member connected with said bag-diaphragm at the opening therein and adapted to screw into the tap-hole, a frame connected with and extending outwardly from said hollow member, a second frame containing a longitudinally slotted portion, curved members pivotally connected at their lower ends with the lower end of the second-referred-to frame with their curved portions at which they extend into said bag-diaphragm, extending outwardly in opposite directions from said last-referred-to frame, links pivotally connected with the other ends of said curved members, a pivot device in the slotted portion of said frame and movable lengthwise of the latter forming a pivotal connection of said links at their other ends therewith, said curved portions extending in intersected relation with the connections between said links and said curved portions being at the side of said point of intersection opposite that at which said curved portions are pivotally connected with said second-referred-to member, means coöperating with said links for drawing them together to move said curved portions away from each other, and means coöperating with said frames for forcing said second-referred-to frame inwardly relative to said first-referred-to frame.

MICHAEL PROVICH.
